United States Patent Office

Des. 196,436
Patented Oct. 1, 1963

196,436

MOBILE RECEIVER-TRANSMITTER

Chester S. Ingraham, East Aurora, Glenn E. Merz, Buffalo, and John A. Meyer, Tonawanda, N.Y., assignors to Sylvania Electric Products Inc., a corporation of Delaware

Filed June 8, 1962, Ser. No. 70,469

Term of patent 14 years

(Cl. D26—14)

Fig. 1

Fig. 2

Fig. 3

FIG. 1 is a perspective view of a mobile receiver-transmitter embodying our new design;

FIG. 2 is a bottom view of FIG. 1; and

FIG. 3 is a rear view of FIG. 1.

The side not shown is substantially a mirror image of the side shown in FIG. 1.

We claim:

The ornamental design for a mobile receiver-transmitter, as shown and described.
